UNITED STATES PATENT OFFICE.

CHARLES S. SMITH, OF PROVIDENCE, RHODE ISLAND.

FABRIC BELT.

1,071,594.

Specification of Letters Patent. Patented Aug. 26, 1913.

Application filed September 16, 1911. Serial No. 649,625.

To all whom it may concern:

Be it known that I, CHARLES S. SMITH, of Providence, in the county of Providence and State of Rhode Island, have invented 5 certain new and useful Improvements in Fabric Belts, of which the following is a specification.

This invention relates to belts for personal wear, especially of the type used by men for 10 the waist bands of trousers, although I do not limit myself to such use, as belts of similar construction may be worn by women and children.

The object of the invention is to provide 15 an improved waist belt which, although the band appears to be of fine and heavy fabric having substantially the body of a leather belt, yet requires only a relatively small quantity of expensive fibrous material to be 20 employed.

To this end the invention consists in a belt having its band portion consisting of a tubular seamless fabric member having an inner or filling member, the two being so 25 constructed and connected as to furnish practically no visible evidence that the band is not a single piece of heavy fabric. By the construction embodied, I am able to furnish handsome belts, at relatively low cost, which 30 can be made of various fibrous materials and in any color, to match or properly contrast with, the material of the garment with which the belt is to be worn.

Of the accompanying drawings,—Figure 35 1 is a perspective view of a complete garment belt constructed according to my invention. Fig. 2 represents a section on line 2—2 of Fig. 1, on a larger scale. Fig. 3 is a perspective view of the outer fabric member or covering of the band. Fig. 4 is a perspective view of the inner member or filler strip. Fig. 5 is a perspective view of the outer and inner members partly assembled. Fig. 6 is a broken out perspective view of 45 the stiffened guide loop. Fig. 7 represents a section on line 7—7 of Fig. 2, but illustrating a modification hereinafter referred to. Fig. 8 represents a section on line 8—8 of Fig. 3. Fig. 9 represents a section on line 9—9 of Fig. 4. Fig. 10 represents a section on line 10—10 of Fig. 5. Fig. 11 is a broken detail view to illustrate the method of forming the pointed end of the belt. Fig. 12 is a detail elevation of the finished 50 55 pointed end. Fig. 13 represents an edge view of the finished pointed end.

Similar reference characters indicate the same or similar parts in all of the views.

The belt comprises, as usual, a band which as a whole is indicated at *a* in Figs. 1 and 2, to one end of which is connected a buckle *b* that may be of any usual or preferred structure. The band consists of a seamless tubular strip of fabric 15 having a filler 16, said tubular strip 15 being preferably woven, 60 although it might be braided without departing from my invention. The tubular member 15 may be of silk, linen or any other fibrous material. It will be hereinafter referred to as the covering or jacket. 65 The filler strip 16 may be, and preferably is, of coarse woven and relatively inexpensive material. It is drawn into the covering or jacket by suitable machinery or tools, and is, in practice, of such width as to spread the 70 covering to a smooth and taut condition. 75 It is shorter than the covering, and is formed with one end 17 straight and the other end formed with a notch or angular recess 18, for reasons presently described. 80 Before the filler strip is drawn in, it is coated or sufficiently impregnated with an adhesive or semi-adhesive compound, preferably a rubber compound, to cause the inner surface of the covering to be so intimately 85 united to the filler strip, when subjected to pressure (and in some cases heat also) applied to the two members, as to prevent any possibility of the fine fabric jacket wrinkling or buckling, or giving the appearance of 90 “blisters” when the belt is flexed, and subjected to the gripping action of the buckle. This rubber compound, besides rendering the covering and filling inseparable, also renders the belt waterproof, so that no perspiration can cause the outer surface of the 95 belt to become discolored.

The reason for the angular recess 18 in the filler strip, is to enable the tip end of the belt to be given a finished appearance 100 and to exhibit no material difference as to thickness or “body” from the rest of the band. As indicated in Fig. 11, the inner and outer members, when assembled, permit the squared end of the covering to project 105 as indicated by the dotted outline. Then said end is tucked in by a suitable tool which is caused to push the corners 19 inward in the direction of the arrows, said corners going in to the position as indicated by the 110 dotted lines 20 in Fig. 12. This results in infolding the fabric so that its multiple

thicknesses resulting from the infolding substantially equal the thickness of that portion which includes the filling strip, and leaves the band with a pointed tip 21. The 5 infolds may have cement applied thereto, and preferably the two edges which meet at the tip 21 are secured additionally by a fine line of stitches 22 (Fig. 13). As shown by comparing Figs. 3, 4, 5 and 11, the strap, 10 which in this particular instance is adapted to be employed as a belt, has its end reinforced or stiffened by turning in the end of the tubular fabric and securing it so; that is, the portion of the strap which contains 15 no filling, and which is composed of seamless tubular fabric only, is so reinforced or stiffened. Said end is therefore adapted to be inserted through any buckle without liability of being curled up. At the other end 20 of the band, the covering extends sufficiently beyond the straight end 17 of the filling strip, to connect the buckle and retaining or guide loop 25 thereto without unduly increasing the thickness of the belt at this 25 point. The said loop is preferably reinforced or stiffened by a metal core 26 (Fig. 6). The extended portion of the covering 15 is folded about the attaching bar of the buckle (Fig. 2), carried back, and the extreme end tucked inside the under side of 30 the loop 25; then two lines of transverse stitches 27, 28, serve to confine both the

buckle and the loop in their relative positions.

As shown in Fig. 2, the straight end 17 of the filling strip terminates just short of the stitch line 27. I do not limit myself to this, however, as said filling may extend also inside the loop 25 to prevent the belt from bending too readily along the line 27. In 40 this case, a section through the loop would show the filling as in Fig. 7.

I do not limit myself to the use of my invention as a belt, since it may be usefully employed as a strap for other purposes. 45

I claim:

1. A strap composed of a seamless tubular woven fabric having a filling strip, one end of said strip being recessed, the corresponding end portion of the tubular fabric being 50 infolded and entering the recess of the strip.

2. A strap comprising a seamless tubular fabric having a close fitting filling of less length than the fabric, one end of the tubular fabric being extended beyond the filling 55 and folded back upon itself, and a buckle engaged by said folded-back portion.

In testimony whereof I have affixed my signature, in presence of two witnesses.

CHARLES S. SMITH.
